UNITED STATES PATENT OFFICE

107,461

DESIGN FOR A COMBINED COAL AND GAS RANGE

Walter D. Teague, Jr., Kew Gardens, N. Y.

Application December 10, 1936, Serial No. 66,464

Term of patent 14 years

To all whom it may concern:

Be it known that I, Walter D. Teague, Jr., a citizen of the United States, residing at Kew Gardens, New York, in the county of Queens and State of New York, have invented a new, original, and ornamental Design for a Combined Coal and Gas Range, of which the following is a specification, reference being had to the accompanying drawing, forming part thereof.

The figure is a perspective view of a combined coal and gas range, showing my new design.

The other side of the range is the same as that shown except that it has two conventional dampers for primary and secondary draft for the coal burning portion of the stove.

I claim:

The ornamental design for a combined coal and gas range, substantially as shown, and described.

WALTER D. TEAGUE, JR.
